UNITED STATES PATENT OFFICE.

CHARLES LEDERHOS, OF NEW YORK, N. Y.

DESIGN FOR AN OIL-STOVE FOUNT.

SPECIFICATION forming part of Design No. 25,463, dated May 5, 1896.

Application filed January 18, 1896. Serial No. 576,043. Term of patent 14 years.

To all whom it may concern:

Be it known that I, CHARLES LEDERHOS, a citizen of the United States, residing in the city, county, and State of New York, have invented and produced a new and original Design for an Oil-Stove Fount, of which the following is a specification.

The leading feature of my design is an oil-stove fount of substantially the configuration and representation shown in the accompanying drawings, in which—

Figure 1 is an elevation of a fount embodying my design. Fig. 2 is a longitudinal section through the fount-reservoir.

In the drawings, A is an upright cylindrical burner located contiguous to a horizontal cylindrical reservoir or fount B, which is hollow, and is helically ribbed on the outside at C, at or near one of its ends, and has ribs b b ar-

ranged in pairs on its outside surface, the spaces between the ribs forming division-bands dividing the exterior of the fount-reservoir into three about equal parts. Cylindrical projections D E extend laterally from the one end of the reservoir in opposite directions. The reservoir is banded between the pairs of ribs b b by bands F, from which bands feet G, in the form of truncated triangles, extend.

What I claim is—

The design for an oil-stove fount substantially as described and shown in the accompanying drawings.
